UNITED STATES PATENT OFFICE.

SAMUEL J. LAUGHLIN, OF GUELPH, ONTARIO, CANADA.

SELF-ACTING ELEVATOR-GATE.

SPECIFICATION forming part of Letters Patent No. 298,482, dated May 13, 1884.

Application filed December 26, 1883. (No model.) Patented in Canada December 4, 1883, No. 18,234.

To all whom it may concern:

Be it known that I, SAMUEL JOHN LAUGHLIN, a citizen of the Dominion of Canada, and a subject of Her Majesty Queen Victoria, residing at the city of Guelph, in the county of Wellington and Province of Ontario, Dominion of Canada, factory foreman, have invented a new and useful Self-Acting Elevator-Gate, (for which I have obtained a patent in the said Dominion of Canada, No. 18,234, bearing date the 4th day of December, 1883,) of which the following is the specification.

This invention relates to certain new and useful improvements in that class of elevators which are provided with self-acting gates; and the invention consists in the peculiar combinations and the construction and arrangement of parts hereinafter described and claimed.

In the accompanying drawings, Figure 1 is a front elevation of an elevator with my improvements attached. Fig. 2 is a side elevation of the same, and Fig. 3 is a plan view.

A is a car or platform, which is operated by any of the well-known means, to which are attached the devices for operating the gate, which consist in the present instance of arms B B, pivotally attached to the car, and supported near their outer ends by pins p, projecting from the standard b. The said arms are shown converging from the pivotal point, and kept in engagement with the guide K by means of springs N. The outer ends of the arms B are provided with a retaining-point, c, and outwardly-flaring flange c'.

L L are guides in which operate the gate E. C H are counterpoises or weights attached, respectively, to the cords F and I, passing over suitable pulleys, G, located at the top of the guides L, and attached to the opposite ends of the gate. The combined weight of the counterpoises should not quite equal the weight of the gate E, as it is designed that the gate should close automatically by its own gravity when the car is ascending or descending, the weights being used simply to reduce or moderate the gravity of the said gate. The weight C is T-shaped, and runs in a correspondingly-shaped groove in the guide K, and has a prolongation, C'', which extends beyond the face of the guide K, and engages with one of the arms B, in a manner more fully hereinafter explained.

In practice, the car rising to the level of the floor S, one of the arms B engages the catch C', attached to the elevator-gate, and carries it to a position shown in dotted lines in Fig. 1, 55 when the passage-way to the car or platform is unobstructed. Upon a further ascent of the car the arm engages with a double-inclined plate, D, suitably located above the floor S, and secured to the guide K, which disengages 60 the arm B from the catch C', and at the same time permits the other arm B to engage the projection C'' on the counterpoise C, and allows the gate to descend. As the car descends from above, the arm B engaging C'' causes the 65 gate to ascend until the car reaches the floor S. On its further downward movement the arm engaging with D disconnects B and C'', and at the same time, C' engaging B and resting on it, the gate descends simultaneously with 70 and at the same rate of speed as the car. It will be noticed that the catches C' C'' are oppositely and outwardly inclined. This arrangement is for the purpose of permitting the arms to ride and easily pass the catch in one 75 direction, so as to be in position to engage the same when the opposite catch and arm are disengaged.

While I have shown and described the elevator-well as having only one gate, it is evident that it may be provided with similar ones on each side.

What I claim as my invention is—

1. In combination with an elevator car or platform provided with suitable devices to 85 open or close a passage-way thereto, a gate, as E, working in ways and partially counterbalanced, and constructed to close the said passage-way by its own gravity, and governed in its movement by the car acting directly on its 90 counter-balance, substantially as specified.

2. In combination with an elevator car or platform and the gate E, the counterpoise C, having projection C'', working in the guide K, and acted on directly by the car or platform, 95 substantially as and for the purposes set forth.

3. In combination with an elevator car or platform and gate E, partially balanced, the counterpoise C, having projection C'' and catch C', attached to the said gate, both arranged substantially as specified, whereby the one engages the car to open a passage-way thereto,

and upon its own release the other engages with the said car to govern the closing of said passage-way, substantially as described.

4. The combination of the gate E and catch C, connected therewith, arms B, attached to the car or platform, and plate D, constructed, arranged, and operating substantially as specified.

5. In an elevator provided with a safety-gate, and as a means for automatically operating the same, the arms B, springs N, catches C' C'', weights C H, guide K, and double-inclined plate D, combined and operating substantially as and for the purposes set forth.

6. In combination with the car or platform 15 of an elevator, and a safety-gate connected therewith, the arms B, provided with the outwardly-flaring projections c', the catches C' C'', oppositely inclined, double-inclined plate D, and guides K, constructed substantially as and 20 for the purposes specified.

In testimony whereof I affix my signature, in presence of two witnesses, this 20th day of December, 1883.

SAMUEL J. LAUGHLIN.
